CLAIM

The ornamental design for a table clamp with latch and disposable docking top, as shown and described.

DESCRIPTION

1. Table clamp with latch and disposable docking top

1.1 is a perspective view.

1.2 is a front view.

1.3 is a back view.

1.4 is a side view.

1.5 is another side view.

1.6 is a top view.

1.7 is a bottom view.
